US00D942988S

(12) **United States Design Patent** (10) Patent No.: **US D942,988 S**
(45) Date of Patent: ** Feb. 8, 2022

(54) **DISPLAY PANEL OR PORTION THEREOF
WITH GRAPHICAL USER INTERFACE**

(71) Applicant: **MAGIC LEAP, INC.**, Plantation, FL (US)

(72) Inventors: **Brian Everett Meaney**, Parkland, FL (US); **Marc Coleman Shelton**, Fort Lauderdale, FL (US); **Megan Ann Geiman**, Fort Lauderdale, FL (US); **John A. Gotcher**, Prosper, TX (US); **Matthew Schon Bogue**, McKinney, TX (US); **Shivakumar Balasubramanyam**, San Diego, CA (US); **Jeffrey Edward Ruediger**, McKinney, TX (US)

(73) Assignee: **Magic Leap, Inc.**, Plantation, FL (US)

(**) Term: **15 Years**

(21) Appl. No.: **29/731,826**

(22) Filed: **Apr. 17, 2020**

Related U.S. Application Data

(62) Division of application No. 29/646,113, filed on May 1, 2018, now Pat. No. Des. 886,836.

(51) LOC (13) Cl. **14-04**

(52) U.S. Cl. **D14/485**

(57) **CLAIM**

The ornamental design for a display panel or portion thereof with graphical user interface, as shown and described.

DESCRIPTION

The FIGURE is a front view of a display panel or portion thereof with graphical user interface showing our new design.

The outermost broken line rectangle illustrates a display panel or portion thereof that forms no part of the claimed design. The remaining broken lines, including all text, illustrate portions of the graphical user interface or mixed reality environment and form no part of the design.

1 Claim, 1 Drawing Sheet
